UNITED STATES PATENT OFFICE.

CHARLES JOSEPH FIRMIN MOLLET-FONTAINE AND LÉON ABEL CELER
LETOMBE, OF LILLE, FRANCE.

GAS-MOTOR.

SPECIFICATION forming part of Letters Patent No. 634,063, dated October 3, 1899.

Application filed November 16, 1897. Serial No. 658,612. (No model.)

To all whom it may concern:

Be it known that we, CHARLES JOSEPH FIRMIN MOLLET-FONTAINE and LÉON ABEL CELER LETOMBE, citizens of the Republic of France, residing at Lille, France, have invented Improvements in Gas-Motors, of which the following is a specification.

The invention hereinafter described is applicable to all kinds of motors capable of acting under the control of a regulator with variable charges of an explosive mixture, the volume of which is consequently independent of the space rendered vacant by the piston in its stroke. In this class of motor, the consumption of gas in which may be very low even with a full charge, the control of the speed has been effected hitherto principally either by the reduction of the explosive mixture admitted or held back by means of an intermediate receptacle or by the simple reduction of the gas. Now these two methods, which are very suitable for avoiding abrupt changes in the speed which are met in the method of control of the ordinary gas-motors, unfortunately diminish the thermic yield in a great measure—the first method in consequence of the diminution of compression, insufficiently compensated by the increase of the period of expansion, and the second method in consequence of deformations of the cycle resulting from the imperfect ignition which occurs when the composition of the explosive mixture is no longer in harmony with the compression requisite in the machine.

The improvements in question have for their object to secure a new method of regulation of gas-engines by means of variable charges without diminution of the thermic yield for the indicated work. This method consists essentially in reducing the force of the charges admitted when the resistance to be encountered tends to become reduced below its maximum by a supercompression caused by the augmentation of the volume of explosive mixture admitted combined with the simultaneous reduction of the percentage of gas in the said mixture in proportion as the said admissions are increased.

In the drawings, Figure 1 is a diagram intended to facilitate the comprehension of our invention. Fig. 2 is a front elevation of the

cylinder of a double-acting gas-engine constructed according to our invention. Fig. 3 shows a plan view of the same cylinder. Fig. 4 is a section on the line $x'y$ of Fig. 2. Figs. 5, 6, 7, and 8 show details of the controlling mechanism.

Referring first to the diagram shown in Fig. 1, which illustrates the full charge of a machine having admission of gas independent of the stroke, the action will be, no matter what the system employed, as if there were admission from a to b , depression, for instance, from b to f during the latter portion of the suction-stroke, compression from f to b during the first portion of the compression-stroke, effective compression from b to c , explosion and expansion from c to d and thence to e , and escape from e to a . If it is desired to obtain a diagram of less area and to effect regulation in conformity with our invention, the admission instead of being diminished will be increased up to a point b' between b and e , and the pressure drops, for instance, from b' to f' during the latter portion of the suction-stroke and reaches again b' . At b' begins the effective compression, which, owing to the increased admission $a'b'$, causes a supercompression at c' , but at the same time we diminish the quantity of gas in the mixture so that the explosion can never exceed the point d , which is a maximum which has been settled previously. For this purpose it is requisite that the volumes of gas admitted during the aspirations $a'b$ and $a'b'$ should be proportioned as the perpendiculars $c'd$ and $c'd'$. Obviously the surface $b'c'd'e$ is less than the surface $bcd e$. At the limit when the motor becomes partly unloaded the admission might be allowed to continue throughout the entire stroke, the proportion of gas being suitably diminished or even suppressed altogether if the machine were too much unloaded. Now calculations will show that the thermic yield of the cycle under consideration increases in proportion as the surface diminishes, as we have indicated above. The supercompression, such as $c'c$, in excess of the normal compression $a'c$ cannot cause any disturbance, because the pressure of the explosion can never exceed a fixed quantity if the gas be reduced successively in such manner as is

above specified. By making use of these means the content in gas of the mixture diminishes consequently in proportions as the admissions increase; but as the compression increases at the same time the ignition remains effective.

As already stated, Figs. 2 to 8 of the drawings show arrangements devised to admit of the application of this method of control to a double-acting gas-engine having a cycle of four strokes. Each end of the cylinder L, Figs. 2, 3, and 4, bears a chamber containing two valves, Fig. 5, one marked A, which communicates with the cylinder L by the port i , Fig. 4, and the other marked B, which communicates with the first by means of the intermediate chamber C, as shown in Fig. 5, which gives a section on the line $z t$ of Fig. 3. This valve B closes in the opposite direction, so as automatically to shut off all communication with the outside whenever a depression tends to be formed in the cylinder L. The two valves A and B can, moreover, as shown in Fig. 5, open in the same direction. The valve B, which can open a little in advance of the valve A, meets on opening with the valve G, which it also raises and which gives access to the gas at m , as shown at Fig. 6, which figure shows a section of these valves on the line $u v$ of Fig. 3. The air is supplied through n , Fig. 5. When the working is regulated by supercompression, the valve B when the resisting load diminishes closes later and later and the gas-valve G, on the contrary, sooner and sooner. At the limit when the machine is finally unloaded the valve B no longer rises sufficiently to actuate the valve G, and a void stroke is produced.

The valves B are actuated by the levers K, Figs. 2 and 4, having rollers J, Fig. 4, which receive their motion from stepped cams P, mounted upon the shaft O, Figs. 2 and 4, actuated directly by the main shaft of the motor. Figs. 7 and 8 show separately one of these stepped cams P. The rollers J, which rest against these cams, can be displaced transversely by the regulating mechanism, (denoted generally by R'), so as to encounter, as will be shown hereinafter, respectively, the

one or the other superposition of the cams P. 5° This operation is effected by means of the articulated parallelogram S T U V and of the clips provided with springs R, which prevent said clips gripping the rollers, Figs. 2 and 4. The duration of the full aspiration 55 corresponds to the angle $y O z'$, Fig. 7. The superposed successive steps of the cams P are shown as shaped at 4 1 2 2' or 4 1 3 3', &c., in which 4 1 corresponds to the advance and 1 2 or 1 3, and so on, to the superposition for the 60 admission of the gas. The empty stroke corresponds to 4 4' without superposition. These arrangements, the use of which is very advantageous for a double-acting motor, are obviously also applicable to single-action motors. 65

Having thus described our invention, we claim—

1. In combination in a gas-engine with the cylinder and piston, a gas-valve and an air-valve, with controlling means for said valves 70 arranged substantially as described upon reduction of the load of the engine to increase the supply of air while reducing that of the gas, substantially as described.

2. In combination, the cylinder, the air-valve B, the gas-valve arranged to be operated thereby and to close sooner than the air-valve with means for controlling the operation of the air-valve B to increase the supply 75 of air while reducing that of the gas upon the reduction of the load of the engine, substantially as described.

3. In combination, the cylinder, the gas-valve, the air-valve arranged to operate the gas-valve and a lever, and graduated cam for 85 operating the air-valve with governor mechanism controlling the valve to increase the supply of air while reducing that of the gas upon the reduction of the load of the engine, substantially as described. 90

In witness whereof we have hereunto set our hands in presence of two witnesses.
